UNITED STATES PATENT OFFICE.

ALEXANDER WILLIAM COPLAND, OF DETROIT, MICHIGAN.

ICING-MACHINE.

No. 848,638.

Specification of Letters Patent.

Patented April 2, 1907.

Application filed November 6, 1905. Serial No. 285,977.

To all whom it may concern:

Be it known that I, ALEXANDER WILLIAM COPLAND, a citizen of the United States of America, residing at Detroit, in the county of Wayne and State of Michigan, have invented certain new and useful Improvements in Icing-Machines; of which the following is a specification, reference being had thereto to the accompanying drawings.

The invention relates to coating-machines, and has more particular reference to machines for icing cakes and other bakery products.

The invention consists in the novel construction as hereinafter set forth.

In the drawings, Figure 1 is a side elevation of the machine. Fig. 2 is a plan view thereof. Fig. 3 is a vertical longitudinal section through a portion of the machine. Fig. 4 is a longitudinal section through a portion of the suction-holder.

Generally described, the machine comprises feeding mechanism for the articles to be coated; a reversible holder to and from which said articles are fed and by which they are held during the coating operation, a receptacle beneath said holder for the coating fluid, and means for periodically raising the surface of the coating fluid into contact with the surfaces of the articles on the holder.

More in detail, A is a suitable frame, at one end of which is arranged a receptacle B for the uncoated articles. As shown, this receptacle is adapted to receive round cakes, and is provided with a plurality of adjacent tubes or cylinders a, arranged transversely across the frame. Each of these tubes is preferably vertically slotted at b to permit of more readily placing the articles therein.

C is a reversible holder, which is arranged adjacent to the receptacle, B, extending transversely of the machine. This holder is preferably of the suction type, and is reversed by rotation about the horizontal axis. It is also preferably provided with two diametrically-opposed suction-heads, so that the one will be in upright position while the other is reversed.

Each of the suction-heads C' C² consists of a hollow casing provided with a flat plate c, upon which the articles are deposited and which is perforated, as at d. Between the heads C' C² the case C is in the form of a hollow cylinder, which communicates with the suction-chambers through longitudinal slots e. This cylinder is sleeved about a stationary

tube D, which is provided on its upper side with a boss f, constituting a valve for closing the slot e of the upper suction-head. At the lower side of the tube D is a slot h, establishing communication between the interior of the tube and the annular passage j between the tube and the cylindrical case. The arrangement just described is such that the holder C may be revolved about the tube D, being provided with suitable journal-bearings D' at opposite ends thereof, and when either of the suction-heads C' C² is in any position save the one centrally above the tube it will be in communication with said tube. Thus when the tube D is connected with a suitable suction apparatus a partial vacuum will be created within the suction-heads sufficient to hold any articles covering the perforations d in the plate c.

The articles are fed intermittently from the receptacle B to the holder C, preferably by a reciprocating pusher E, which slides upon the table F. This table extends beneath the receptacle C and is spaced therefrom by a distance equal to the thickness of one cake, and thus the pusher which extends across the frame will in each operation simultaneously extract a series of cakes from the several tubes a and feed them over the table F onto the plate c, which is arranged in the same plane.

In addition to the pusher E the mechanism is provided with a second pusher G, the function of which is to remove the cakes from the holder C after they have been carried by the latter through one complete revolution. This pusher G is arranged in advance of the pusher E on the opposite side of the receptacle B and is operated simultaneously with the first pusher. Thus it

will cross the plate c in advance of the depositing of a series of cakes thereon from the receptacle B and will push off the series of cakes on said plate, depositing them on the aligned conveyer-belt H. In order that the pusher G in its return movement will not shove backward the series of cakes which is deposited on the holder C, guides are provided for forcing it through a different path of movement. These guides I I' are preferably arranged upon opposite sides of the frame over which the pusher-bar G travels in its return movement, being sufficiently above said frame to clear the bar. At the end of the guides are point-switches J J', which are pivoted to permit the bar G to pass under, but in

105

110

to the top of the guides I I', so that it will clear the line of deposited cakes upon the holder C. An antifriction-roll g is preferably arranged at the opposite ends of the bar G to travel upon the frame A and guides I I', thereby reducing friction.

Beneath the holder C is a tank or receptacle K, containing the icing fluid, and the arrangement is such that when the holder C is given a half-revolution the cakes or articles thereon will be suspended in inverse position directly above the icing fluid. To coat the articles, the level of the fluid must be raised, and this I preferably accomplish by displacement. As shown, L is a chamber at the bottom of the tank K, in which a piston M is fitted, this chamber and piston preferably extending the full width of the tank.

h' is a partition separating the chamber L from the upper portion of the tank, and i is a slot in this partition extending, preferably, the full width of the tank.

j' is a flange extending across the upper portion of the tank and upward from the partition h', but having its upper edge below the upper edges of the receptacle K.

With the arrangement just described an inward movement of the piston M within the chamber L will force the fluid contained therein upward through the slot i, raising the level of the fluid in the upper portion of the receptacle K until the upper edge of the flange j' is reached. Any further displacement of the fluid by the piston M will cause an overflow over the flange j' without further raising the level of the fluid. Thus the height to which the fluid is raised is exactly predetermined and is such that the articles on the holder C will be coated without depositing any of the icing material upon the holder itself. In the return movement of the piston M the fluid is again drawn down into the chamber L or is sufficiently depressed to provide clearance for the holder during its rotary movement.

The surplus icing material adhering to the articles after the coating operation is removed by a scraper. This preferably comprises a scraping-blade N, which extends transversely of the machine and is carried by a rock-frame O, pivotally secured at P preferably to the tank K. Q is an antifriction-roll carried by a rock-lever R, also pivoted at P, said roll being adapted to be engaged with a flange S at the end of each suction-head C' C'. T is an adjustable link connecting the lever R with the rock-frame O. The object of this construction is to maintain the scraper-blade N a fixed distance from the plate c of the suction-head during the rotation of the latter, and this distance may be adjusted by means of the link T. Thus the blade N may be set so as to scrape off the surplus icing material, leaving a coating upon the articles of uniform thickness. The ma-

terial removed by the blade N will drop off therefrom into an extension K' of the receptacle K and will be returned to the body of icing fluid.

The various parts of the apparatus thus far described are operated from a common drive mechanism in properly-timed relation, preferably through mechanism of the following construction: U is a drive-pulley on a shaft U', journaled in the frame, and U² U³ are intermeshing gears respectively on said shaft U and a parallel shaft V. Upon the shaft V is mounted a cam V', which operates a rock-arm V², connected by a link V³ with a lever V⁴, said lever being connected to a rod V⁵ for actuating the piston M. Upon the same shaft V is also mounted a cam W, which actuates a rock-arm W', link W², and lever W³, the latter being connected by a link W⁴ with the pusher E. The pusher G is also actuated by this mechanism through the medium of pivotal links G', which extend upon opposite sides of the frame and are pivotally attached at G² to the pusher E. The shaft V has also attached thereto a crank X, which is pivoted to a bearing-block X', slidably engaging a slotted rock-arm X², pivoted at X³. Y is a link connecting the block X' with a rock-arm Y', pivoted upon a shaft Y² and intermittently rotating said shaft through the medium of a pawl Y³ on the rock-arm engaging a ratchet or notched wheel Y⁴ on the shaft. Y⁵ and Y⁶ are intermeshing gears respectively on the shaft Y² and rotary holder C, by which the latter is given an intermittent rotary movement. H is a feed-belt onto which the coated articles are delivered from the holder C, said belt being intermittently actuated by a suitable feed mechanism which I deem it unnecessary to describe in detail.

In the operation of the machine the cakes or other articles to be coated are placed by the attendant in the several tubular holders a of the receptacle B, the lower cake resting upon the table F. Motion being imparted to the various parts of the machine through the mechanism described, the first movement in the coating operation will be the transfer of a series of cakes from the bottom of the receptacle B to the holder C, this being effected by the forward movement of the pusher E. When the cakes are thus deposited upon the plate c of one of the suction-heads C' C', motion will be communicated through the crank X, sliding bearing X', rod Y, rock-arm Y', pawl Y³, and ratchet-wheel Y⁴ to the shaft Y² and from the latter, through the intermeshing gears Y⁵ and Y⁶, to the holder C, the amount of movement being just sufficient to turn said holder through a one-half revolution, thereby reversing the positions of the suction-heads. During the initial movement of the holder C the slot e, communicating with the chamber in the upper suction

head, will be carried out of registration with the valve-face f , thereby establishing communication between said suction-chamber and the interior of the conduit D , which is connected to a suitable suction apparatus. The cakes will thus be caused to adhere to the plate e of the suction-head and will remain suspended in inverse position after the completion of the first movement of the holder C . The piston M is next actuated through the medium of the rod V^9 , lever V^4 , link V^3 , rock-arm V^1 , and cam V^2 , forcing the icing fluid upward in the receptacle K until it reaches the upper edge of the flange j , at which level the surface of the cakes will be immersed in the fluid. The piston is then returned to depress the level of the fluid, whereupon motion is again imparted to the rotary holder C , carrying the coated cakes back to the position where they were first deposited upon the holder. During this movement the flange S will engage with the antifriction-roll Q and cause the movement of the scraper-blade N , so as to maintain it a fixed distance from the plate e of the suction-head, removing the surplus material from the cakes and returning it into the receptacle K .

The operations just described constitute one complete cycle; but simultaneously with the movement of the pusher E the pusher G is actuated, as has been previously described. Thus the coated articles are removed from the holder C by the pusher G in advance of the depositing of the uncoated articles thereon, both operations occurring during the interval in which the holder C is stationary. The pusher G carries the coated articles onto the feed-belt H , by which they are removed or further operated upon by mechanism constituting no part of the present invention.

What I claim as my invention is —

1. In a coating-machine, the combination of a periodically-reversing holder for the articles to be coated, and an automatic feeding means for said articles to and from said holder, operating during the interval when the latter is in upper position.
2. In a coating-machine, the combination with a periodically-reversing holder, of means for simultaneously feeding the uncoated and coated articles respectively to and from said holder.
3. In a coating-machine, the combination with a periodically-reversing holder, of a pair of pushers traveling in the plane of the holding-face, the one in advance of the other and the advance pusher traveling completely across the holder, means for depositing the articles to be coated in the path of the rear pusher whereby they are fed onto the holder, and means for returning the forward pusher through a different path, avoiding the deposited articles, whereby in subsequent operation said deposited articles are removed from the holder by said forward pusher.

4. In a coating-machine, the combination with a rotary holder periodically operated to be reversed in position, a pair of pushers traveling in the plane of said holder in initial position, the one in advance of the other and an advance pusher traveling across the holder, a receptacle for the uncoated articles from which they are fed into the path of the rear pusher and carried thereby onto said holder, means for returning the forward pusher through a path avoiding the articles deposited on the holder, and timed operating mechanism whereby said pushers are simultaneously operated during the interval of rest of said holder and said holder is reversed in position intermediate successive forward operations of said pushers.

5. In a coating-machine, the combination of a container for the coating fluid, a reversible holder for the article to be coated thereabove and a feed mechanism to and from said holder in the plane thereof while in upper position.

6. In a coating-machine, the combination of a container for the coating fluid, a reversible holder thereabove having diametrically-opposed holding-surfaces and a lateral feed mechanism to and from said holder in the plane of the upper holding-surface.

7. In a coating-machine, the combination of a holder for the article to be coated in inverted position, a container for the coating fluid therebeneath and means for raising the coating fluid from varying levels to an exactly-predetermined level.

8. In a coating-machine, the combination with a reversible holder for the article to be coated, of a container for the coating fluid therebeneath and means operating when the holder is in the coating position for raising the surface of the fluid by displacement to a predetermined level.

9. In a coating-machine, the combination with a holder for the inverted article, of a container for the coating fluid therebeneath, and means for contacting the article with said fluid and then separating it therefrom, a scraper for removing the surplus material from the coated surface and a guide for the scraper, for the purpose described.

10. In a coating-machine, the combination with a movable holder for the article to be coated, of a container for the coating fluid, and means for automatically raising and lowering the surface of the fluid while the holder is in the coating position, for the purpose described.

11. In a coating-machine, the combination with a holder for the article to be coated, of a container for the coating fluid in operative relation thereto, a cylinder communicating with said container, a piston in said cylinder arranged to force fluid from said cylinder into said container, said container having an overflow outlet at the height of the required fluid-

level in the container, for the purpose described.

12. In a coating-machine, the combination with a container for the coating fluid, of a holder for the articles to be coated arranged to be moved from a loading position to a position in operative relation to said container and thence to an unloading position, a suction means operating to hold the articles on said holder, and means for raising the surface of the fluid into contact with the articles when said holder is in the coating position.

13. In a coating-machine, the combination with a container for the coating fluid, of a reversible holder for the articles to be coated, means for causing the surface of the fluid to contact with the articles when said holder is in its reversed position, an adjustable scraper for removing the surplus fluid from the article, and a guide for the scraper, substantially as described.

14. In a coating-machine, the combination with a holder and means for feeding articles onto said holder, of a pusher reciprocating across said holder, and means compelling said pusher to take different paths in its advance and return movements, for the purpose described.

15. In a coating-machine, the combination with a holder for the articles, of a pusher, means for reciprocating said pusher across said holder, and means compelling said pusher to take different paths in its advance and return movements, for the purpose described.

In testimony whereof I affix my signature in presence of two witnesses.

ALEXANDER WILLIAM COPLAND.
